UNITED STATES PATENT OFFICE.

SYLVESTER T. COHANE, OF HARTFORD, CONNECTICUT.

SILENCER FOR TELEPHONES.

Application filed February 15, 1922. Serial No. 536,790.

To all whom it may concern:

Be it known that SYLVESTER T. COHANE, a citizen of the United States, residing at Hartford, in the county of Hartford and 5 State of Connecticut, has invented certain new and useful Improvements in Silencers for Telephones, of which the following is a specification.

This invention relates to a silencer for 10 telephones. Among the objects of the invention are the provision of an article of this character which can be inexpensively and easily made, readily applied and by the employment of which the user of a telephone 15 can conduct a conversation thereover without likelihood of being heard by those in his vicinity.

In the drawing accompanying and forming part of the present specification I have 20 shown in detail one of the several forms of embodiment of the invention which to enable those skilled in the art to practice the same will be set forth fully in the following description. Clearly I am in no way 25 restricted to this disclosure. I may depart therefrom in several respects within the scope of the invention defined by the claims following said description.

Referring to said drawing:—

30 Figure 1 is a side elevation of a telephone instrument furnished with a silencer involving the invention and showing a way of using it.

Fig. 2 is a cross section on the line 2—2 35 of Fig. 1 looking in the direction of the arrow.

Fig. 3 is a sectional view of the silencer showing it applied to the mouth piece of the telephone.

40 Like characters refer to like parts throughout the several views.

In Fig. 1 I have shown the familiar telephone which is denoted in a general way by 2 being provided with the transmitter 3 having the customary mouth piece 4. The receiver and its hook are not shown because they do not concern the invention. At the present time in using the mouth piece 4 it is practically impossible, except when in a 45 booth, to transmit speech without those near hearing and my primary motive as will be inferred, is to accomplish this thing without likelihood of those near the user hearing what is transmitted.

55 The silencer is denoted in a general way

by 5 and it has means by which it can be detachably connected with the mouth piece 4. It is usually made of some flexible material such as rubber, and comprises a body as 6 which is virtually of circular formation. 60 Said body 6 comprises an inner wall 7, an outer wall 8 and a side wall as 9 which as will be understood, is desirably annular or circular, although I am not restricted in this regard. The inner wall has practically centrally thereof the opening 10 surrounded externally by the outwardly flared nipple 11 having near its free edge the rabbet 12 which 65 removably fits over and receives the outer edge portion of the telephone mouth piece 4. 70 In other words the silencer is practically connected with the telephone mouth piece in an air tight manner.

As shown the inner wall 7 has internally thereof the two annular flanges 13 which receive between them the single flange 14 of the outer wall so as to provide within the body 6 a tortuous silencing-passage.

The outer wall 8 as shown has a practically central opening 15 which is surrounded, within the body 6 by an annular flange 16, the depth of which equals that of the flange 14 and aids with them in securing the tortuous passage to which I have referred.

The body 6 is provided with an outwardly flared mouth-piece 17 which virtually constitutes a continuation of the flange or tube 16 and which is intended to receive the mouth of the user.

I have found in practice that by putting 90 the mouth into this mouth-piece 17 speech can be transmitted without likelihood of being heard close to the instrument, the mouth piece being sufficiently enlarged to receive the human mouth.

The silencing effect I find can be augmented by providing the wall 7 with one or more perforations as 18.

What I claim is:—

1. A telephone silencer comprising a body 100 involving inner and outer approximately parallel circular walls and a cylindrical wall connected with the peripheral portions of the inner and the outer walls to provide a hollow structure, a plurality of staggered 105 annular walls inside the body, spaced from each other and connected respectively rigidly with the inner and the outer circular walls to provide a tortuous passage, the inner wall of the body having means for de- 110

tachable connection with a telephone mouthpiece, the outer wall having a mouthpiece to receive the mouth of a user.

2. A telephone silencer comprising a body involving inner and outer approximately parallel circular walls, and a cylindrical wall connected with the peripheral portions of the inner and the outer walls to provide a hollow structure, a plurality of staggered annular walls inside the body, spaced from each other and connected respectively rigidly with the inner and the outer circular walls to provide a tortuous passage, the in-

ner wall of the body having means for detachable connection with a telephone mouthpiece, the outer wall having a mouthpiece to receive the mouth of a user, the outer wall of the body having a tube surrounded by and spaced from the inner annular wall and constituting a continuation of the mouthpiece. 15 20

In testimony whereof I affix my signature.

SYLVESTER T. COHANE.

In presence of:—

MARY F. LONG,
HEATH SUTHERLAND.
